(57) **CLAIM**

What is claimed is the ornamental design for a chisel holder, as shown and described.

DESCRIPTION

FIG. 1 is an upper front perspective view of the chisel holder.

FIG. 2 is a front elevation view of the chisel holder of FIG. 1.

FIG. 3 is a rear elevation view of the chisel holder of FIG. 1.

FIG. 4 is a top view of the chisel holder of FIG. 1.

FIG. 5 is a left side elevation view of the chisel holder of FIG. 1; and,

FIG. 6 is a right side elevation view of the chisel holder of FIG. 1.

The dashed lines are shown for environmental purposes only and form no part of the claimed design.
